DESIGN FOR A COMBINED JAR AND CLOSURE

Michael S. Desser, Toledo, Ohio, assignor to Owens-Illinois Glass Company, Toledo, Ohio, a corporation of Ohio

Application October 5, 1934, Serial No. 53,494

Term of patent 14 years

To all whom it may concern:

Be it known that I, Michael S. Desser, a citizen of the United States, and residing at Toledo, in the county of Lucas and State of Ohio, have invented a new, original, and ornamental Design for a Combined Jar and Closure, of which the following is a specification, reference being had to the accompanying drawing, forming a part thereof.

In the drawing:

The figure is a side elevational view of a combined jar and closure showing my design.

I claim:

The ornamental design for a combined jar and closure substantially as shown.

MICHAEL S. DESSER.
